CONTROL AND RESETTING MECHANISM
FOR FLUID DISPENSING APPARATUSIrving C. Jacobs, Longmeadow, Mass., assignor to
Gilbert & Barker Manufacturing Company,
West Springfield, Mass., a corporation of Massachusetts

Application September 27, 1949, Serial No. 118,084

13 Claims. (Cl. 222—32)

1

This invention relates to improvements in fluid measuring and dispensing apparatus and, more particularly, to such apparatus as is adapted for dispensing measured quantities of gasoline or the like.

The general object of the invention is to provide in a gasoline dispensing apparatus improvements which simplify the work of the operator and make it easier and more convenient for him to service the fuel tank of an automobile.

According to one object of the invention, a single control member is provided outside the pump casing mounted for movement back and forth throughout a predetermined range and operable, when moved from one limit to the other of such range, to effect a complete cycle of movement of the resetting shaft of the register and then to start the pump motor, whereby resetting of the register must be effected before pumping can commence, said member being operable when moved from the last-named to the other limit, to stop the motor without actuating said shaft.

According to another object of the invention, the single control member may be part of a swivelled mounting for the delivery hose so that as the hose nozzle is carried to the tank to be serviced, the hose will be pulled to turn the said part of the swivelled mounting and cause resetting of the register and starting of the pump motor without any special effort or attention on the part of the operator.

According to another object of the invention, the mounting includes a rigid pipe, having a vertical portion, rotatably mounted adjacent one side of the pump casing to turn about its own axis, and a transverse portion, to the outer end of which the hose is connected, this transverse portion being high enough to clear the top of the pump casing, when such portion is turning, and long enough to extend from one side to the other of the casing, such pipe being turnable to any desired position through a 360° range to provide for convenience in servicing and for extension of the servicing range.

The invention has for another object the provision of means, preferably interlocked with the nozzle and nozzle support, for holding said pipe in one predetermined angular position, when the hose is not in use, such position being one wherein the transverse portion of the rotatable pipe overlies the top of the casing.

The invention has for another object the provision of actuating connections between the rotatable pipe and the register of the apparatus

2

for resetting the latter by the movement of the rotatable pipe through a predetermined angle from a predetermined initial radial position, and preferably irrespective of the direction in which the rotatable pipe turns.

These and other objects will best be understood from the detailed description of the examples of the invention with reference to the accompanying drawings, in which:

10 Fig. 1 is a front elevational view of a liquid dispensing apparatus embodying the invention, the front cover being removed to reveal interior mechanism;

Fig. 2 is a side elevational view of the apparatus;

15 Fig. 3 is a fragmentary sectional elevational view of the apparatus, drawn to a larger scale and showing the mounting of the swinging pipe, the register, the resetting means for the register, and the means for actuating the switch of the pump motor;

Fig. 4 is a fragmentary sectional plan view taken on the line 4—4 of Fig. 3;

20 Fig. 5 is a cross sectional view taken on the line 5—5 of Fig. 3;

Figs. 6 and 7 are fragmentary sectional views taken on the lines 6—6 and 7—7, respectively, of Fig. 5;

25 Figs. 8 and 9 are fragmentary cross sectional views taken on the lines 8—8 and 9—9, respectively, of Fig. 3;

Fig. 10 is a view taken similarly to Fig. 9 and showing a modification;

30 Fig. 11 is a side elevational view of another form of dispensing apparatus, not having a pivoted arm for hose extension;

Fig. 12 is a fragmentary sectional elevational view, drawn to a larger scale and showing the same register-resetting mechanism actuated with the motor switch by a handle interlocked 35 with the hose nozzle;

Figs. 13, 14 and 15 are fragmentary cross sectional views taken on the lines 13—13, 14—14 and 15—15, respectively, of Fig. 12;

40 Fig. 16 is a fragmentary sectional plan view, taken similarly to Fig. 4 and showing another modification of the invention, consisting of separate means operated by the swinging pipe for actuating the motor switch;

Fig. 17 is a fragmentary sectional elevational view taken similarly to Fig. 3 and showing the switch-actuating cam;

45 Fig. 18 is a fragmentary cross sectional view, taken similarly to Fig. 5 and showing the resetting gearing and switch-actuating means;

Fig. 19 is a fragmentary sectional elevational view showing the clutch between the resetting gearing and the resetting shaft of the register; and

Fig. 20 is a view, taken similarly to Fig. 5 and showing another modification in the register-resetting means.

Referring to these drawings and first to Figs. 1 and 2 thereof, the invention is shown, by way of illustrative example, as embodied in a gasoline dispensing apparatus of well known form. Such apparatus includes a pump 1, driven by an electric motor 2, through the belt 3 and pulleys 4 and 5, and adapted to draw up fluid such as gasoline, from an underground supply tank (not shown) through a suction pipe 6 and force it outwardly through a delivery conduit, which includes a flexible hose 7, having on its outlet end a valved hose nozzle 8. As shown herein, this delivery conduit includes a pipe 8' connecting the outlet of pump 1 to an air separator 9, a pipe 10 connecting the outlet of separator 9 to the inlet of a meter 11 and a pipe 12 connecting the outlet of the meter, by means later to be described in detail, to a swivelled pipe 13 to the outer end of which hose 7 is connected by means of a suitable coupling 14. Interposed in pipe 13 at its highest point, is a visible discharge indicator 15 of any suitable or desired form.

The meter 11, which measures the fluid dispensed, drives through a shaft 16, a register 17, which indicates the amount of fluid dispensed in quantity, cost or both. As shown, the register is of the well known computing type and has number wheels 18, visible through openings 19 in a dial plate 20 for showing the quantity of fluid dispensed, in gallons and fractions thereof, and other number wheels 21 visible through openings 22 in said plate for showing the cost of the fluid dispensed, in dollars and cents. The register may, for example, be of any suitable type, such as the well known Veeder-Root type or the type shown in the DeLancey Patent No. 2,390,239, granted December 4, 1945.

The apparatus described, except for the hose 7, and pipe 13, is enclosed in a suitable upright casing and supported from a suitable frame located within the casing in any suitable way. As herein shown, the frame includes a base 23, angle iron columns 24 fixed to and upstanding from the base and an inner cap 25, which ties together the upper ends of the four columns. The casing has a cap 26, supported by the inner cap 25, and front, back and side panels 27, 28 and 29, respectively, which enclose the space between the base 23 and cap 26. The columns 24 carry platforms 30 and 31, the former supporting the motor 2 and pump 1 and the latter the register 17.

The swinging pipe arm 13 is mounted, as best shown in Figs. 3 and 4. Extending across between a pair of the columns 24 and secured at its ends thereto is a plate 32. Bolted to this plate is a casting 33, which extends outwardly through an opening 34 in the adjacent side panel 29. This casting has mounted therein axially-spaced upper and lower bearings 35 and 36, which rotatably support the vertical portion of pipe 13. The casting 33 has on its upper face a race for a plurality of balls 37, upon which rest a disk 38, fixed to the pipe 13. The said upper face, the disk and the balls serve as a thrust bearing to support the pipe 13. This pipe is held against upward displacement by a collar 39, fixed to its lower end and engaging the lower end face of bearing 36. The lower end of pipe 13 is open and in constant

communication with a chamber 40, formed in a casting 41, fixed to the lower face of casting 33 and closing the chamber 40. The only other communication with chamber 40 is by way of the described pipe 12. The metered fluid from pipe 12 thus flows through chamber 40, and pipe 13 to hose 7. Leakage from chamber 40 is prevented by two seal rings 42, which are mounted on pipe 13 between the bearings 35 and 36 and forced apart by a spring 43 and thereby pressed, one against the upper face of bearing 36 and the other against the lower face of bearing 35. The casting 33 is preferably enclosed by a casing 44, suitably fixed to side panel 29. Casing 44 has in its upper end a circular opening bounded by an upstanding annular rim 45. Fixed to pipe 13 is a circular cap 46 which overlies the opening and has a downturned annular rim 47 overlapping the rim 45.

When the apparatus is not being used, the pipe 13 overlies the cap 26 of the pump casing, extending from one side to the other thereof, and the hose is then disposed in a long loop, extending downwardly from the outer or free end of pipe 13 toward the bottom of the pump casing and then upwardly toward the top of the casing, where the nozzle 7 rests on a suitable support, such as 48. The spout of the nozzle usually lies in a boot 49 to protect it from the weather and, when so located, a portion of the guard 50 for the valve lever 51 of the nozzle rests on the support. As best shown in Fig. 3, the guard has an opening therethrough to receive an upstanding ear 52 on the nozzle support 48. The ear is perforated to receive a padlock to enable the nozzle to be locked to the support. When the apparatus is used for dispensing, the nozzle is removed from its support and carried to the tank to be serviced. In so doing, the pipe 13 will be swung to one side or the other of its normal or neutral position and it may be swung through varying angles to extend the service range. The pipe 13, when turned 180 degrees from neutral position, effects the maximum increase in the service range, which is about twice the length of the pipe. It may be turned to a lesser extent, according to requirements, but it will always be turned at least 45 degrees from neutral position for any servicing. Of course, the pipe can turn 360 degrees, if necessary or desired.

To assist the operator in locating pipe 13 in various positions, recesses such as 53 may be provided in the periphery of disk 38 and a spring-pressed detent 54 mounted on casting 33 in position to engage in any of the recesses as the disk is turned. As shown one notch is located so as to be engaged by the detent, when pipe 13 is in neutral position, and the other notches are spaced at 45 degree intervals therefrom.

Aside from the advantage of increasing the servicing range of the pump, the swivelled pipe 13 may be utilized as a control member, operable by its movement to effect resetting of the register 17 and then the starting of the pump motor 2, and subsequently operable to effect stopping of the motor. For this purpose, an actuating cam is provided, fixed to pipe 13. In this case, a cam path 55 is formed in the upper face of the described disk 38 to receive a roll 56 mounted on a lever 57, which is pivoted at one end on a stud 58 fixed to an upstanding hub on casting 33. The cam path 55 is constructed so that when pipe 13 is turned through a predetermined angle, say for example 30 degrees, in either direction from its neutral position, the lever 57 will be

moved its full stroke (to the left as shown in Fig. 4). Further rotation of the pipe causes the roll 56 to engage in a dwell portion of the cam, whereby the pipe 13 can thus turn without moving the lever. When the pipe is turned back to its neutral position, the lever 57 will be moved back, during the last 30 degree part of its movement, into the position illustrated. This lever is arranged by any suitable transmission to operate a mechanism to reset the register and to actuate the switch of the pump motor 2. As illustrated herein, such transmission consists of a Bowden wire 59, one end of which is connected to lever 57, and a sheath 60 for the wire, one end of which sheath is held by a suitable anchor 61 to plate 32, or any other stationary part of the apparatus. The Bowden wire and its sheath extend across the pump casing over the top of register 17 and then downwardly to the mechanism for resetting the register, later to be described.

In one form of register, there is a shaft 62, which, when turned through a predetermined angular extent, in this case 405 degrees, in one direction (clockwise as viewed in Fig. 8) will reset the number wheels to zero. This shaft will then be turned back, by means within the register, through an angle of 45 degrees, making the net movement of shaft 62, 360 degrees or one revolution. As shown in Fig. 8, the shaft 62 has fixed thereon a ratchet 63 and a disk 64, having a single radial notch 65 in its periphery. A spring-pressed pawl 66 cooperates with ratchet 63 and is normally engaged with ratchet tooth 67. A member 68 is mounted to swing on a shaft 69 of the register and carries near its lower end a roll 70 adapted to engage in notch 65. A spring 71, connecting member 68 to some stationary part of the register, tends to turn member 68 clockwise and through roll 70 to turn disk 64 counterclockwise but is unable to do so on account of the engagement of pawl 66 with ratchet tooth 67. The resetting shaft 62 is thus held from rotating reversely from the position shown. To reset the register, shaft 62 is turned clockwise. As it is thus turned, the first action is to move roll 70 to the right and stress spring 71. This action continues for 45 degrees, when roll 70 will ride out of notch 65 and onto the periphery of disk 64, where it will not exert any force on the disk tending to turn it backward. During this 45 degree interval, the usual clutches (not shown) will be actuated to disconnect each set of number wheels from the meter driving mechanism and then connect them to the resetting shaft 62, all as disclosed in the aforesaid patent. The first tooth 72 of ratchet 63 has an angular extent of slightly more than 45 degrees. One can therefore turn shaft 62 through the initial 45 degree movement and then move it backward to its normal and illustrated position. However, after resetting has commenced, which occurs just after the initial 45 degree movement of shaft 62 is completed, the latter cannot be restored to its initial position by reverse rotation because of pawl 66 and ratchet 63. Shaft 62 can then be turned only in a forwardly or clockwise direction. Thus, resetting, once initiated, must be completed. After the shaft 62 has been turned 405 degrees, the disk 64 will move under roll 70 and the latter will drop into the notch 65. Then, spring 71, acting through member 68 and roll 70 will turn disk 64 backwardly (counterclockwise) into the position shown, the long tooth 72 permitting this reverse movement. Resetting will have been

completed prior to this reverse movement of shaft 62 and during such reverse movement, the clutches of the register will be actuated to disconnect the number wheels from shaft 62 and reconnect them to the driving mechanism actuated by meter shaft 16.

Not all forms of registers employ reverse movement of the resetting shaft after the end of the resetting movement but those that do employ such reverse movement, present special difficulties in adapting this invention for use with them and they will be considered first, bearing in mind that there are other forms of registers, wherein a predetermined movement of the resetting shaft in one direction only will effect resetting.

The reset shaft 62 (Fig. 3) extends outside the casing of register 17 and has fixed to its outer end a socket member 73, which is connected by means of a shaft 74 to a socket member 75, fixed on the inner end of a short shaft 76, which is rotatably mounted in a hub of a plate 77 and which has fixed to its other end a pinion 78. The pinion is the terminal element of the resetting gearing, which is actuated by the above described Bowden wire 59. The plate 77 is fixed at its ends, one to each of two of the columns 24, and supports such gearing. The shaft 74 connects the two socket members 73 and 75 and allows one to be driven from the other even if the two sockets are not exactly aligned. Each socket member has a cylindrical socket to receive a ball 79 on the end of shaft 74. The peripheral wall of each socket has two diametrically-opposite longitudinally-disposed slots 80 therein, to slidably receive the projecting ends of a cross pin 81, fixed in ball 79 and extending diametrically therethrough.

The reset gearing includes a gear 82, which is rotatably mounted on a stud 83, fixed at one end in plate 77, and which meshes with pinion 78. Mounted at one end on stud 83 with freedom to turn is a pawl 84, adapted to engage ratchet teeth 85, fixed on gear 82. A spring 86, acting between a collar 87 on stud 83 and the pawl arm 84, presses the latter into position where it is effective to engage and drive one of the ratchet teeth. This arm 84 is connected to the lower end of the described Bowden wire 59, the sheath 60 of which is anchored at 60' to plate 77. Thus, swinging of the pipe 13 will oscillate the pawl arm. In this particular case, the cam is constructed to swing pawl 84 through $\frac{1}{64}$ of a revolution. The ratio of gear 82 to pinion 78, in this case, is 8 to 1, the gear 82 having 64 teeth for example, and the pinion 78 having 8 teeth. The pawl 84 initially abuts one ratchet tooth as shown, when pipe 13 is in its neutral position. When arm 84 is moved in either direction from neutral position, through an angle of say 30 degrees, the pawl 84 will swing upwardly $\frac{1}{64}$ of a revolution and turn gear 82 counterclockwise by the same amount, or nine teeth. This will drive pinion 78 clockwise nine teeth or one and one eighth revolutions and shaft 62 will thus be turned the required amount to complete resetting of register 17. Fixed to plate 77 is a cam 88, arranged in the path of pawl 84 and adapted, when the latter reaches the end of its upward stroke, to release the pawl 84 from the tooth, which it had theretofore been driving. On such release of the pawl, the spring 71 of the register will very rapidly turn the reset shaft 62 backwardly (counterclockwise) by an angle of 45 degrees. This will turn pinion 78 one tooth in a counterclockwise direction, whereby gear 82 will

be turned one tooth in a clockwise direction, bringing it beneath pawl 84 so that the latter, when subsequently released from the cam 88 during the initial part of its return or downward movement cannot become drivingly engaged with such tooth. The pawl 84 will be swung downwardly just far enough to engage beneath the next ratchet tooth of the series in position for a subsequent resetting operation in the manner described.

The switch for stopping and starting the pump motor 2 is contained within the casing of the motor and is usually of the toggle type. This switch is operated by pulling or pushing on a Bowden wire, contained within a sheath 90 which, as shown in Fig. 1, extends upwardly in the pump casing. The upper end of this sheath is shown in Fig. 5, fixed by an anchor 91 to a plate 92, which in turn is fixed at its ends to two of the angle iron columns 24. The upper end of Bowden wire 93 is shown as fixed to a lever 94. Lever 94 is pivotally supported intermediate its ends on a stud 95, fixed to plate 92, and has at one end a roll 96, pressed against the periphery of a cam 97 by means of a spring 98, which connects the lever to plate 92. The cam 97 is mounted to turn on a stud 99, fixed to plate 92, and is turned by means of a link 100, which connects it to pawl 84. The cam 97 has a dwell surface 101 on which roll 96 rides, until the pawl 84 reaches the end of its upward stroke, when the roll rides off this dwell surface onto a steep drop 102. The spring 98 would move roll 96 quickly to the bottom of this drop 102, except for a dashpot 103, the piston 104 of which is connected by its rod 105 to lever 94. The descent of piston 104 is limited by the small area of the vent 106 of the dashpot, whereby the closing of the motor switch is delayed and made to occur after the pawl 84 has reset the register. The switch, being of the toggle type is not actuated until at the very end of the stroke of lever 94.

The cam 97, lever 94, spring 98 and dashpot 103 provide for a time delay between the actuation of the register-resetting means and the closing of the motor switch. This time delay, while desirable as insurance that the motor switch cannot be closed until resetting of the register has been completed, may not in all cases be necessary. As will later appear, the Bowden wire 93 may be connected to the pawl 84 without the intermediary of the time delay device described. Ordinarily, if the motor switch is closed at the same time that the gear 82 has completed its resetting movement, the 45 degree reverse movement of the register shaft 62 will be effected almost instantaneously by spring 71 and before the operator will have time to open the valve of the hose nozzle and thereby cause movement of shaft 16 and the number wheels of the register 17.

The shaft 99, to one end of which cam 97, is fixed, is mounted in a bearing 107, fixed to the outer face of plate 92 and extending through and beyond the adjacent side panel 29. On the outer and upper part of the bearing is mounted the nozzle support 48, heretofore described. Such support is pivoted to the bearing at 108 and is urged upwardly by a spring 109. When the spout of nozzle 8 is placed in boot 49, the lower and horizontal part of the guard 50 of nozzle 8 is swung inwardly and deposited on the pivoted support 48, whereupon the latter moves downwardly under the weight of the nozzle into the position shown, in which the outer end of sup-

port 48 lies in a recess in a collar 110, fixed to the outer end of shaft 99. When the switch of motor 2 is open and the parts of the resetting gearing are positioned as shown, the recess in collar 110 is positioned so as to receive the hose support 48. When collar 110 is in any other position, as it is when the motor switch is closed and pipe 13 swung out of its normal rest position, the support 48 rides on the periphery of collar 110 and the nozzle 8 cannot then be hung up. Thus the operator must restore pipe 13 to its normal or neutral position before he can hang up the hose nozzle. When the nozzle is hung up, as described, its interlock with collar 110 prevents the pump 1 from being started, the resetting means from being actuated and the pipe 13 from being swung away from neutral position.

If desired, an interlock collar 111, such as shown in Fig. 10, may have a recess wide enough to directly receive the guard 50 of the hose nozzle 8. In this case, the bearing 107 would then serve as a stationary hose support and the pivoted member 48 and its spring 109 can be eliminated.

In operation, the operator must first remove the nozzle 8 from its support 48 or 107, as the case may be, before he can swing pipe 13 by pulling on the hose. The interlock between the nozzle and collar 110 or 111, as the case may be, locks pipe 13 in its neutral position against rotation and hence prevents the operator from starting the pump motor. Having removed the nozzle 8 from its support, the operator carries it to the tank to be serviced and, in so doing, swings pipe 13 away from its neutral position. Ordinarily, in moving the nozzle to the tank to be serviced, the pipe 13 will be swung far enough to actuate the resetting gearing, as described, and then close the motor switch, all without any effort or attention on the part of the operator. However, if the pump doesn't start, the operator will have to pull on the hose to swing pipe 13 far enough to effect the resetting of the register and the closing of the motor switch. The swinging pipe enables extension of the service range, whenever required, and enables easy servicing of cars on either side of the island, on which the pump is ordinarily mounted. The pump control and the register resetting occur automatically by the pulling of the hose necessary to carry the nozzle into servicing position.

For use where hose extension by means of a swinging pipe is not needed or desired, the pump shown in Figs. 11 to 15 is provided. This pump is constructed like the one, above described, except that the swinging pipe 13 and associated devices are omitted and the delivery hose 7 emerges from the opening near the top of one of the side panels 29, the hose being suitably connected inside the pump casing with pipe 12. Suitable visible discharge indicators 112 are also provided in the delivery conduit and extend through the front and back panels 27 and 28 of the pump casing, as indicated in Fig. 11. The hose nozzle 8, when its spout is inserted in boot 49, is supported by the horizontal portion of its guard 50 resting on top of a fixed support 113, which is fastened at its inner end to plate 92 and extends outwardly through the side panel 29. Near the outer end of support 113 is an upstanding ear 114, which passes through a slot in guard 50 and is perforated to receive a padlock, whereby the nozzle may be locked to its support.

The resetting gearing is the same as hereto-

fore described but the control member, which actuates it, consists of a small handle 115 instead of the swinging pipe 13. This handle 115 is fixed to the outer end of a shaft 116, which is rotatably mounted in support 113 and has fixed to its inner end a lever 117. The outer end of this lever is connected by a link 118 to the pawl 84 which actuates the resetting gearing. The Bowden wire 93, which actuates the switch of the pump motor, is also connected to lever 117 by means of a suitable connecting piece 119. On the inner end face of the hub of handle 115 is formed a lug 120, having radial sides adapted to abut one or the other of two radial stop faces 121 and 122, formed on the nozzle support 113. These stops 121 and 122 limit the extent of swinging movement of handle 115 to exactly that necessary to swing pawl 84 through an angle equal to that between successive ratchet teeth 85 and to that necessary to move the motor switch between its "on" and "off" positions. When handle 115 is positioned, as shown in Figs. 12 and 13, so that its lug 120 abuts stop 121, the pawl 84 is in its extreme lower position and the motor switch is open. Clockwise movement of the handle 115 to start the pump motor or reset the register 17 is prevented, when nozzle 8 is hung up on its support 113, by an upstanding ear 123 on the handle, which abuts a portion of guard 50 that projects outwardly beyond the outer end of nozzle support 113. When nozzle 8 is removed from support 113, handle 115 may be moved clockwise until it abuts stop 122. This will cause pawl 84 to be raised far enough to actuate the resetting gearing, in the same manner as heretofore described, and also move the motor switch to "on" position. When dispensing is finished, the operator must swing handle 115 counterclockwise until the lug 120 abuts stop 121 in order to hang up the nozzle on its support and, in so doing, the motor switch is moved to "off" position and the pawl 84 is restored to its lower position in readiness for a subsequent actuation to reset the register.

Another form of the invention is illustrated in Figs. 16 to 19. In this, as well as in the first form of the invention, the control member is the swinging pipe 13 and it is mounted and operates in the same way as described in connection with Figs. 1 to 5. The casing 44 and cap 46 will be used but these have been omitted in Fig. 17. However, in addition to cam 55, which actuates the Bowden wire 59, a separate path cam 124 is provided in a disk 125, fixed to pipe 13, for the purpose of actuating the motor switch and a clutch, to be later described, in the resetting gearing. A roll 126, mounted on and depending from a lever 127, rides in cam 124. Lever 127 is pivoted at one end on a stud 128, fixed to member 33 and has attached to its other end one end of a Bowden wire 129. The sheath 130 for this wire is anchored at its upper end, together with the upper end of sheath 60, by means of a clamp 131, which binds it to a bracket 132 fixed to plate 32. The lower end of sheath 130 is fixed by an anchor 133 to plate 17. The lower end of the Bowden wire 129 is fixed to the outer end of a horizontal arm 134, fixed at its inner end to one end of a shaft 135. Also fixed to shaft 135 adjacent arm 134 is a clutch-shifting fork 136. The shaft 135 is rotatably mounted in a bearing 137, fixed to plate 17, and is held in axial position by the engagement of the hub of fork 136 and a collar 138, which is fixed to the

shaft, with opposite end faces of the bearing 137. The fork 136 has trunnions engaged in a circumferential groove 139 in a clutch element 140. This element is axially slideable on a shaft 141, which is rotatably mounted in a bearing on plate 17. Shaft 141 has fixed to its outer end a pinion 142 and to its inner end a clutch element 143. The members 142 and 143 abut opposite sides of the bearing for shaft 141 and serve to retain the shaft in proper axial position. The outer end face of element 140 and the inner end face of element 143 have teeth such as 144, which are normally held engaged but may be disengaged by axial movement of element 140 to the left by means of the clutch fork 136, actuated by Bowden wire 129. This clutch element 140 has on its inner face a socket 145, similar to the heretofore described socket 73 on the reset shaft 62 of register 17 and connected to socket 73 by a shaft 146, which has ball ends to fit in the sockets and cross pins in the ball ends to fit in slots in the side walls of the sockets in the same manner as heretofore described in connection with shaft 74. A spring 147, coiled around shaft 146, acts between two washers 148 on the shaft 146 to press against the end faces of sockets 73 and 145 and press the clutch element 140 toward and into engagement with its cooperating element 143.

The arm 134 is connected by a link 149 to the upper end of a connector strip 150, the lower end of which is attached to the Bowden wire 93, which actuates the motor switch. The strip 150 is pivotally connected at a point intermediate its ends to one end of an arm 151, the other end of which is fixed to the inner end of the shaft 99, in place of the cam 97, heretofore described. This shaft 99 is mounted, as before, and carries on its outer end a collar, such as 110, for interlocking with the hose nozzle support, as heretofore described.

The Bowden wire 59, actuated by cam 55, serves, as in the first form of the invention, to oscillate a pawl. This pawl, marked 152, is mounted in the same way as pawl 84, and is engageable with ratchet teeth 153 fixed to a gear 154, which is rotatably supported from plate 17 in the same way as gear 82. Gear 154 meshes with pinion 142. The ratio of gear 154 to pinion 142 is 9 to 1. The ratchet teeth 153 are spaced 45 degrees. The cam 55 is arranged to move pawl 152 45 degrees. Thus, the gear 154 will be turned one eighth of a revolution on each upward stroke of pawl 152 and will thus turn pinion 142, one and one eighth revolutions, which is what is required to reset the register 17. The cam 124 is designed not to move lever 127 until after cam 55 has moved pawl 152 through its complete upward stroke. Then cam 124 acts to move Bowden wire 129 far enough to cause clutch elements 140 and 143 to disengage and to cause the motor switch to move from "off" to "on" position. Actually, the clutch element 140 moves beyond the position where its teeth disengage from the teeth on element 143. On disengagement of the clutch elements, the reset shaft 62 of the register will move backwardly 45 degrees and come to rest. This occurs before the end of the stroke of arm 134, while the motor switch is not moved to "on" position until the very end of the stroke. Thus, the switch cannot be closed until after the resetting shaft 62 comes to rest. The teeth of the clutch elements are spaced 45 degrees, so that when the clutch elements are subsequently moved into engagement, there will be no lost motion

11

between them. Thus, on a subsequent clockwise movement of pinion 142, the clutch element 143 will immediately pick up and move clutch element 140 so that reset shaft will again be turned the required amount, in this case one and one eighth revolutions.

If desired, the time delay means shown in the first form of the invention may be used, the cam 97 being fixed to shaft 99 in place of lever 151 and the Bowden wire 93 being actuated from the cam through a lever which is pulled by a spring against the resistance of a dash pot.

In operation, when the operator wishes to service a car, he removes nozzle 8 from its support and the latter disengages from the notch in collar 110 and allows the pipe 13 to turn. In carrying the nozzle 8 to the tank of the car to be serviced, the pull on hose 7 will swing the pipe 13 and thus turn cams 55 and 124. The cam 55, when turned a predetermined amount, say 30 degrees, in either direction from the neutral position illustrated will pull Bowden wire 59 and cause pawl 152 to swing upwardly and through a ratchet tooth 153 turn gear 154 far enough to turn shaft 141 one and one eighth revolutions. Since the clutch elements 140 and 143 are then engaged, shafts 146 and 62 will be turned clockwise by the same amount which completely resets the register. The pinion 142 and gear 154 are held stationary by pawl 152 and the register spring 71 is unable to move shaft 62 backwardly (counterclockwise) until the clutch elements disengage. These disengage after pipe 13 has turned a predetermined amount, say 15 degrees, further, and following the disengagement of the clutch, the motor switch is closed and pumping commences. After the desired amount of fluid has been dispensed, the operator returns the nozzle to its support and, as he does so, the pipe 13 is swung toward its neutral position. The first action is for cam 124 to move Bowden wire 129 to allow the clutch elements 140 and 143 to reengage and the motor switch to be moved to "off" position. This is followed by the action of cam 55, which through Bowden wire 59 will move pawl 152 downwardly until it snaps over and behind the next succeeding tooth of the ratchet. The nozzle cannot be placed on its support until the motor switch has been opened and this occurs only at the end of the swinging movement of lever 151. Thus, the operator must move pipe 13 completely back to neutral position before he can hang up the hose nozzle. The engagement of the spring-pressed detent 54 in a notch in disk 38 will help the operator in locating the pipe properly in neutral position.

As mentioned above, certain registers provide for resetting by a predetermined movement of the resetting shaft in one direction only without the reverse movement described. As one example, one such register requires its resetting shaft to be turned two revolutions in order to reset the number wheels to zero and then this shaft comes to rest. The invention may very readily be arranged for use with registers of this type simply by omitting the clutch means, which permit the reverse movement, and making appropriate changes in the resetting gearing. These changes are indicated in Fig. 20. Assume that the shaft 76 is connected, in a manner similar to that described, to a resetting shaft which needs to be turned two full revolutions in a clockwise direction to move the number wheels of the register back to zero. A gear 82, having ratchet teeth 85, moved by pawl 84 by Bowden wire 59,

12

as formerly, meshes with a pinion 155, mounted on a stud 156, fixed to plate 77. Pinion 155 has fixed thereto a gear 157, which meshes with an idler gear 158 mounted on a stud 159 fixed to plate 77 and the idler gear 158 meshes with the pinion 78 on shaft 76. As an example, gear 82 has 64 teeth, the ratchet teeth 85 are spaced 45 degrees, pawl 84 has a stroke of 45 degrees, pinion 155 has 8 teeth, gear 157 has 16 teeth and pinion 78 has 8 teeth. Thus, the pawl when pulled upwardly by Bowden wire 59 will turn gear 82, one eighth of a revolution counterclockwise or 8 teeth. This will cause pinion 155 and with it gear 157 to be turned one revolution clockwise. Gear 157 through idler gear 158 will turn pinion 78 in a clockwise direction and the full two revolutions required for resetting. The link 109 may connect pawl 84 as before to actuate the motor switch, closing it when the pawl reaches the end of its upward stroke. While pumping occurs, the resetting shaft of the register remains stationary and all of the gears described will remain stationary. After the desired amount of fluid has been dispensed, the pipe 13 is returned to neutral position, thereby pushing on the Bowden wire and moving pawl 84 downwardly without moving gear 82, the pawl finally coming to rest beneath the ratchet tooth next succeeding the one which it had theretofore driven. Also, the motor switch will be opened when pawl 84 reaches the end of its downward stroke.

In all forms of the invention a relatively simple mechanism is provided for resetting the register and controlling the pump motor so that dispensing cannot occur until the register has been reset and so that resetting cannot occur during dispensing. This is effected simply by swinging a control member (the pipe 13 or handle 115 or equivalent means) from one extreme to another of a predetermined range of movement and without any necessity for the relatively complicated and expensive interlocks, heretofore used between the pump control lever and the register-resetting shaft.

The invention also provides, in the case of the swinging pipe 13, a means whereby the resetting of the register and starting of the pump are effected, without requiring any particular attention or effort on the part of the operator, by the act of moving the hose nozzle into position to service the tank of an automobile.

The swinging pipe 13 also enables easy servicing of the tank of an automobile from either side of the island, on which a pump is often mounted, and enables a desirable extension of the servicing range, since the pipe can swing to any position throughout a 360 degree range. Also, the extension of the hose is effected without requiring extra exertion on the part of the operator as is required, where spring-retracted reels or other spring or weight-retracted hose-storage means are used. Such reels or means require the operator to pull the hose out against the resistance of the retracting spring and to hold it extended under tension. Here, the extension requires no substantial added effort. The operator simply carries the nozzle, wherever he wishes to go, and the pipe swings as much as required and in the direction required, and during the initial stages of the swinging in either direction resetting of the register occurs followed by starting of the pump motor.

Thus, substantially improved means have been provided for controlling a fluid dispensing ap-

paratus, materially simplifying and facilitating the servicing of the fuel tanks of automobiles.

What is claimed is:

1. In a fluid dispensing apparatus, having a delivery conduit including a flexible hose having a nozzle on its delivery end, means for forcing fluid through said conduit, a meter interposed in said conduit for measuring the fluid dispensed, a register driven by the meter for indicating the amount of fluid dispensed and having a shaft operable when turned in one direction to a predetermined angular extent to reset the register, and a casing enclosing the aforesaid elements except for the hose and nozzle, a control member located outside said casing and movable back and forth between first and second positions in which it is respectively operable to start and stop said fluid forcing means, a driving member connected to said shaft and movable step by step in one direction to turn such shaft in the first-named direction, the length of each step of movement of said driving member being that necessary to turn said shaft through said predetermined angular extent; and an actuator connected to said control member to move back and forth therewith and connected to said driving member to move the latter in said one direction only, by one such step and during the movement of the control member from its first to its second position, each such step being completed when and only when the control member moves into said second position.

2. In a fluid dispensing apparatus, having a delivery conduit including a flexible hose having a nozzle on its delivery end, means for forcing fluid through said conduit, a meter interposed in said conduit for measuring the fluid dispensed, a register driven by the meter for indicating the amount of fluid dispensed and having a shaft operable when turned in one direction to a predetermined angular extent to reset the register, and a casing enclosing said meter, register, means and part of said conduit leaving the hose and nozzle outside the casing; a control member located outside said casing and movable back and forth between first and second positions in which it is respectively operable to start and stop said fluid-forcing means, a driving member connected to said shaft and operable when moved in one direction by a predetermined distance to turn such shaft in its resetting direction through said predetermined angular extent, a ratchet connected to turn said driving member and having successive teeth so spaced that when moved from one tooth to the next it turns said member said predetermined distance, a pawl for actuating said ratchet, and connections between said pawl and control member for reciprocating the pawl and operable to move it through its ratchet advancing stroke by and during the movement of said control member from its first-named to its second-named position, the stroke of said pawl being equal to the spacing of said teeth.

3. In a fluid dispensing apparatus, an upright casing, a delivery conduit located in part within said casing, a meter interposed in said conduit for measuring the fluid dispensed and located within the casing, a register in the latter for indicating the amount of fluid dispensed, means for resetting said register, said conduit including a rigid pipe section having a portion mounted adjacent one side of said casing for rotation about a vertical axis and a transverse portion high enough to clear the top of said casing when

the pipe is rotated, said conduit also including a flexible hose connected at one end to the outer end of said transverse portion and a nozzle connected to the other end of the hose, releasable means operable when the hose is not in use to hold the transverse portion of said pipe section against rotation in one radial position overlying the top of said casing, said transverse portion being rotatable when said last-named means is released, and means operable by turning movement of said transverse portion through a predetermined angle from said one radial position to actuate said resetting means.

4. In a fluid dispensing apparatus, an upright casing, a delivery conduit located in part within said casing, a meter interposed in said conduit for measuring the fluid dispensed and located within the casing, a register in the latter for indicating the amount of fluid dispensed, means for resetting said register, said conduit including a rigid pipe section having a portion mounted adjacent one side of said casing for rotation about a vertical axis and a transverse portion high enough to clear the top of said casing when the pipe is rotated, said conduit also including a flexible hose connected at one end to the outer end of said transverse portion and a nozzle connected to the other end of the hose; means for forcing fluid through said conduit, meter and hose; releasable means operable when the hose is not in use to hold the transverse portion of said pipe section against rotation in one radial position overlying the top of said casing, said portion being rotatable when said last-named means is released, and means operable by turning movement of said transverse portion through a predetermined angle from said one radial position to another radial position to start said fluid-forcing means and operable by the movement from the second toward the first radial position to stop said fluid-forcing means.

5. In a fluid dispensing apparatus, an upright casing, a delivery conduit located in part within said casing, a meter interposed in said conduit for measuring the fluid dispensed and located within the casing, a register in the latter for indicating the amount of fluid dispensed, means for resetting said register, said conduit including a rigid pipe section having a portion mounted adjacent one side of said casing for rotation about a vertical axis and a transverse portion high enough to clear the top of said casing when the pipe is rotated, said conduit also including a flexible hose connected at one end to the outer end of said transverse portion and a nozzle connected to the other end of the hose, releasable means operable when the hose is not in use to hold the transverse portion of said pipe section against rotation in one radial position overlying the top of said casing, said transverse portion being rotatable when said last-named means is released, and means operable by turning movement of said transverse portion through a predetermined angle in either direction from said one radial position to actuate said resetting means.

6. In fluid dispensing apparatus, having a casing, a delivery conduit located in part in said casing, a meter interposed in said conduit for measuring the fluid dispensed and located in said casing, means for forcing liquid through said conduit and meter, and a register in the latter driven by the meter for indicating the amount of fluid dispensed, said register having a shaft for resetting it, said shaft being turnable in one direction through one predetermined angular

range to reset the register and then moving reversely through another predetermined angular range and coming to rest, a single control member located outside said casing and movable from a first to a second position and vice versa and operable when moved into the second position to start said fluid-forcing means and when moved into the first position to stop such means, gearing connected to said reset shaft, pawl and ratchet means for intermittently turning said gearing by steps of predetermined angular extent, connecting means between the pawl and control member, whereby the control member in moving from its first to its second position moves the pawl to advance the ratchet and gear by one said step and in moving back to its first position moves the pawl without moving the ratchet, said ratchet when turned one step being operable through said gearing to move the reset shaft in the first-named direction and to the first-named predetermined angular extent, and a clutch associated with said gearing and operable at the end of each said step to disconnect the gearing from the resetting shaft and allow the latter to move reversely through the second-named predetermined angular range.

7. In fluid dispensing apparatus, having a casing, a delivery conduit located in part in said casing, a meter interposed in said conduit for measuring the fluid dispensed and located in said casing, means for forcing liquid through said conduit and meter, and a register in the latter driven by the meter for indicating the amount of fluid dispensed, said register having a shaft for resetting it, said shaft being turnable in one direction through one predetermined angular range to reset the register and then moving reversely through another predetermined angular range and coming to rest, a single control member located outside said casing and movable from a first to a second position and vice versa and operable when moved into the second position to start said fluid-forcing means and when moved into the first position to stop such means, gearing connected to said reset shaft, pawl and ratchet means for intermittently turning said gear by steps of predetermined angular extent, connecting means between the pawl and control member whereby the control member in moving from its first to its second position moves the pawl to advance the ratchet and gearing by one said step and in moving back to its first position moves the pawl without moving the ratchet, said ratchet when turned one step being operable through said gearing to move the reset shaft in the first-named direction and to the first-named predetermined angular extent, and means operable at the end of each step of movement of the ratchet to disconnect the pawl therefrom and allow the reset shaft to move reversely through the second-named predetermined angular range.

8. In a fluid dispensing apparatus, an upright casing, a delivery conduit located in part within said casing, a meter interposed in said conduit for measuring the fluid dispensed and located within the casing, a register in the latter driven by the meter for indicating the amount of fluid dispensed, means for resetting said register, said conduit including a rigid pipe section having a vertical portion mounted on said casing for rotation about its own axis and having another portion extending transversely of the first portion and of the casing and high enough to clear the top of said casing when the pipe section is rotated, said conduit also including a flexible hose

connected at one end to the outer end of said transverse portion and a nozzle on the other end of the hose, means for forcing fluid through said conduit including a motor, releasable means operable when the hose is not in use to hold said transverse portion in one predetermined radial position, said transverse portion being rotatable in either direction when the last-named means is released, a transmission from said pipe section to said resetting means operable when said transverse portion is turned through a predetermined angle from said predetermined radial position to actuate the resetting means and reset the register, and a switch for controlling said motor and actuated by movement of said transverse portion from an "off" position, when the transverse portion is in said predetermined radial position, to an "on" position, when said transverse portion has been moved through said predetermined angle to reset the register, and vice versa.

9. In a fluid dispensing apparatus, an upright casing, a delivery conduit located in part within said casing, a meter interposed in said conduit for measuring the fluid dispensed and located within the casing, a register in the latter driven by the meter for indicating the amount of fluid dispensed, means for resetting said register, said conduit including a rigid pipe section having a vertical portion mounted on said casing for rotation about its own axis and having another portion extending transversely of the first portion and of the casing and high enough to clear the top of said casing when the pipe section is rotated, said conduit also including a flexible hose

20 25 30 35 40 45 50 55 60 65 70 75

connected at one end to the outer end of said transverse portion and a nozzle on the other end of the hose, means for forcing fluid through said conduit, releasable means operable when the hose is not in use to hold said transverse portion in one predetermined radial position, said transverse portion being rotatable in either direction by pulling on the hose when the last-named means is released, and control means for said fluid-forcing means actuated by movement of said pipe section and operable when the transverse portion is in said predetermined radial position, or in any radial position within a predetermined angular range in either direction therefrom, to maintain said fluid-forcing means stopped and operable in another and larger angular range of movement to maintain the fluid-forcing means in operation and operable when moved from the first range into the second and from the second range into the first to respectively start and stop said fluid-forcing means.

10. In a fluid dispensing apparatus, an upright casing, a delivery conduit located in part within said casing, a meter interposed in said conduit for measuring the fluid dispensed and located within the casing, a register in the latter driven by the meter for indicating the amount of fluid dispensed, means for resetting said register, said conduit including a rigid pipe section having a vertical portion mounted on said casing for rotation about its own axis and having another portion extending transversely of the first portion and of the casing and high enough to clear the top of said casing when the pipe section is rotated, said conduit also including a flexible hose connected at one end to the outer end of said transverse portion and a nozzle on the other end of the hose, means for forcing fluid through said conduit, releasable means operable when the hose is not in use to hold said transverse portion in one predetermined radial position, said transverse portion being rotatable in either direc-

tion when the last-named means is released, a transmission from said pipe section to said resetting means operable when said transverse portion is turned through a predetermined angle from said predetermined radial position to actuate the resetting means and reset the register.

11. In a fluid dispensing apparatus, an upright casing, a delivery conduit located in part within said casing, a meter interposed in said conduit for measuring the fluid dispensed and located within the casing, a register in the latter driven by the meter for indicating the amount of fluid dispensed, means for resetting said register, said conduit including a rigid pipe section having a vertical portion mounted on said casing for rotation about its own axis and having another portion extending transversely of the first portion and of the casing and high enough to clear the top of the casing when the pipe section is rotated, said conduit also including a flexible hose connected at one end to the outer end of said transverse portion and a nozzle on the other end of the hose, means for forcing fluid through said conduit, releasable means operable when the hose is not in use to hold said transverse portion in one predetermined radial position, said transverse portion being rotatable in either direction when the last-named means is released, a control member in said casing movable from one position to another to start and stop the fluid forcing means, a transmission between said section and member for moving the control member back and forth between said positions by movement of said transverse portion back and forth through a predetermined angle, a support for said nozzle when not in use; and an interlock member driven by said transmission and movable adjacent said support, said interlock member being movable, when said control member is moved into position to stop said fluid-forcing means, into a position for interlocking engagement with the nozzle, when the latter is placed on said support, whereby to hold said transverse portion in one radial position against rotation, said interlock member, when moved to any other of its positions, interfering with the placing of the nozzle on the support, whereby said transverse portion must be turned to move said control member into position to stop said fluid-forcing means before the nozzle can be placed on its support.

12. In a fluid dispensing apparatus, an upright casing, a delivery conduit located in part within said casing, a meter interposed in said conduit for measuring the fluid dispensed and located within the casing, a register in the latter driven by the meter for indicating the amount of fluid dispensed, said register having a resetting shaft turnable in one direction through a range comprising one revolution plus a predetermined fraction of a revolution to reset the register and then in the other direction through said predetermined fraction of a revolution, said conduit including a rigid pipe section extending trans-

versely of the casing and mounted at one end on the casing for rotation about a vertical axis, said conduit also including a flexible hose connected at one end to the other end of said pipe section and a nozzle on the other end of the hose, means for forcing fluid through said conduit, releasable means operable when the hose is not in use to hold said pipe section in one predetermined radial position, said pipe section being rotatable when the last-named means is released, a transmission from said pipe section to said shaft for turning the latter in the first-named direction throughout said range when said section is turned a predetermined angle from said predetermined radial position, said transmission including clutch means for driving said shaft in the first-named direction and enabling turning of said shaft in said reverse direction through said angle without turning said section.

13. In a fluid dispensing apparatus, an upright casing, a delivery conduit located in part within said casing, a meter interposed in said conduit for measuring the fluid dispensed and located within the casing, a register in the latter driven by the meter for indicating the amount of fluid dispensed, said register having a resetting shaft turnable in one direction through a range comprising one revolution plus a predetermined fraction of a revolution to reset the register and then in the other direction through said predetermined fraction of a revolution, said conduit including a rigid pipe section extending transversely of the casing and mounted at one end on the casing for rotation about a vertical axis, said conduit also including a flexible hose connected at one end to the other end of said pipe section and a nozzle on the other end of the hose, means for forcing fluid through said conduit, releasable means for holding said pipe section in one predetermined radial position when the hose is not in use, a transmission from said pipe section to said shaft for turning the latter in the first-named direction only and to permit reverse turning of said shaft, and actuating means for said transmission operable by predetermined movement of said pipe section in either direction from said predetermined radial position to turn the transmission always in said first direction.
